UNITED STATES PATENT OFFICE.

EDWARD E. JOHNSON, OF ST. PAUL, MINNESOTA.

DEEP-WELL PUMP.

Application filed June 13, 1919. Serial No. 383,902.

To all whom it may concern:

Be it known that I, EDWARD E. JOHNSON, a citizen of the United States, residing at St. Paul, in the county of Ramsey and State 5 of Minnesota, have invented certain new and useful Improvements in Deep-Well Pumps, of which the following is a specification.

My invention relates to deep well pumps 10 and particularly to double-stroke geared pumps having two pump rods for reciprocating two pump plungers in opposite directions toward and away from each other. An object is to provide a pump-head for pumps 15 of this character with simple rugged and compact mechanism capable of quiet and sustained operation. Another object is to provide a substantial case or body enclosing the operating mechanism so as to exclude 20 dirt and to which automatic lubrication by pump or other means can be applied so that the pump can be operated safely from a distant point or with infrequent attention. Another object is to provide a pump-head 25 which has unusual length of stroke which occupies low head room and is easily adapted to electric or other motor connection. Another object is to provide easy means of 30 connecting and disconnecting the pump-head to and from the pump rods so that the latter may be withdrawn from the well when necessary.

The full objects and advantages of my invention will appear in connection with the 35 detailed description thereof and the novel features embodied in my inventive idea will be particularly pointed out in the claims.

Referring to the accompanying drawings, which illustrate the application of my in- 40 vention,—

Fig. 1 is a view in vertical section. Fig. 2 is a view similar to Fig. 1 showing the operating parts in a different position. Fig. 3 is a view in vertical section at right angles 45 to the position in Fig. 2. Fig. 4 is a view in cross-section on the line 4—4 of Fig. 2. Fig. 5 is a view in cross-section on the line 5—5 of Fig. 3. Fig. 6 is a detail view showing a portion of the gearing. Figs. 7 and 8 are detail views at right angles to each other 50 of the crank device. Fig. 9 is a side view showing the construction for mounting the internal ring gear in the pump-head. Fig. 10 is a view in elevation of a preferred form of pump-head showing a system of lubrica- 55 tion, means for disconnecting and laterally displacing the pump-head and means for alining and supporting the drop pipe. Fig. 11 is a view in elevation at right angles to Fig. 10. Fig. 12 is a top plan view of a 60 drop pipe supporting and alining spider. Fig. 13 is a sectional elevation of a floating stuffing box for the side rods.

Referring to the particular construction shown in Figs. 1 to 6, inclusive, which show the pump hung from the top and independently of the well casing 10, the pump barrel or tubing is designated by the character 12 and near the pump end thereof are two water plungers adapted to be operated 65 alternately toward and away from each other. As shown in Fig. 1, the lower plunger 14 is secured to a solid reciprocating rod 16 and the upper plunger 18 is secured to a hollow reciprocating rod 20 surrounding the solid rod 16 for sliding movement 70 relatively thereto. The upper end of the pump tubing is secured to a support 22, the lower portion of which is formed by a partition 24 into a discharge chamber 26. A 75 discharge pipe 30 is connected to the chamber 26 and a cross-head 32 is adapted to reciprocate within the upper portion of the support. To the cross-head 32 is secured the tubular pump rod 20 which passes through 80 a gland 34 secured to the partition to make a water-tight fit. The support 22 as shown in Figs. 1, 2 and 3 is secured to channel bars 85 36 which constitute the support for a gear casing or body 38 having a bottom 40 provided with a gland 42 through which passes the solid pump rod 16 to the upper end of 90 which is secured a rack 44 having teeth on the two opposite sides thereof. To the cross-head 32 are secured two rods 46 passing 95 through glands 45 in the bottom of the casing, the upper ends of these rods being provided with racks 47. The gear casing is bulged out at 48 to accommodate a shaft 50 to the end of which is secured a driving 100 pulley 52, and upon the shaft are secured two pinions 54 meshing with gears 56 which are journaled on studs 58 mounted in the casing, as best shown in Fig. 5. Internal ring gears 60 are rigidly secured within the casing and are concentric with gears 56. Spur gears 62 mesh with the internal ring gears 60, the spur gears being one-half the dia- 105

ter of the internal gears. The double crank 61 has end bearings 64 journaled in gears 56 between their centers and peripheries. The gears 62 are rigidly mounted on the 5 crank 61 adjacent the end bearings 64 and are concentric therewith. The crank-pin 66 has its axis in the pitch circles of the gears 62. In operation the rotation of the gears 56 carries the gears 62 in an annular path, 10 thereby rolling them around within the internal gears 60. Since the latter are twice the diameter of the gears 62 the crank-pin 66 moves through a diametral line of the internal gears 60 and vertically when, as 15 shown, the crank-pin 66 and end journals 64 are in a vertical plane at the end of the stroke. In practice one internal gear 60 and spur gear 62 in mesh therewith may be omitted without detriment to the action, one pair 20 or two being used as desired. Journaled upon the crank-pin is a bearing member 68 to which the upper end of the rod 16 and the lower end of the rack 44 are attached so as to be in alinement with each other. 25 The rod 16 and the rack 44 are, therefore, reciprocated in a straight line without having any lateral movement and the inwardly-facing racks 47 are in order to secure a compact and rigid structure placed closely adjacent on either side. The gear case or body 30 has journaled therein pinions 74 meshing with the double rack 44 and also with the racks 47. Rollers 76, also journaled in the gear casing 38, engage the outer edges of the racks to support them for reciprocating 35 movement. A supplemental casing 70 attached to the body covers the racks, pinions and rollers in order to exclude dirt. The rack 44 and the racks 47 will be reciprocated in reverse directions relatively to each other and through the attached pump rods 40 will reciprocate the plungers 14 and 18 alternately toward and away from each other. It will also be seen that neither the rack 44 and the rod 16 nor the racks 47 and the rods 45 and 20 have any lateral force applied to them by the driving mechanism. Oil-retaining stuffing boxes 42 and 45 are placed in the bottom of the body 38 around the rods 50 16 and 46.

Figs. 7 and 8 show a desirable construction for mounting the spur gears 62 on the double crank 61 so as to economize space and so as to form a rigid construction. The 55 crank 61 is preferably made of cast steel. The crank cheeks are formed of comparatively thin and large overlapping disks 82 and 78, the latter being concentric with the end bearings 64. The portion of the cheek 60 comprising the disk 78 lies within the gear 62 and adjacent the web 80 of the gear to which it is secured by bolts 84.

Fig. 9 shows a desirable manner of attaching the internal gears 60 within the gear 65 casing. The latter is provided with flanges

86 at opposite sides, the internal gears being secured thereto by screw-bolts 88. Gaps in these flanges are left at the top and bottom so as not to interfere with the up-and-down movement of the crank. 70

Figs. 10, 11 and 12 show a construction by means of which the pump rods may be disconnected in order that the pump-head may be slid back out of the way. The cross-head to which the hollow rod 20 is attached is deflected upwardly to form arms 90 which in their uppermost position extend above the base 36 and to which the rods 46 are attached; at the same time the bearing member 68 having the rod 16 attached to it by the nut 115 is in its lowest position and can be reached through the plate 116 in the case. The rods are detached by unscrewing the nuts 115 and 117 and the pump-head can then be slid back out of the way. A spider 92 is supported by the base 36 and this spider has its transverse arms 94 spaced apart sufficiently to permit reciprocation of the cross-head. Rods 96 depending from the spider serve to support a discharge T 90 98 to which the top of the pump casing or drop pipe is secured and to which the discharge pipe 30 is connected. In order that the pump-head may have its rods in axial alinement with the drop pipe 12 when in 95 operation, the spider 92 is leveled and alined up with it and set-screws 118 bearing in sockets in the base 36 or other suitable means are provided to maintain the alinement. 100

Figs. 10 and 11 show a lubricating system for the pump-head. An oil reservoir 100 is connected by a pipe 102 with a small pump 104 driven by a pulley 106. This pump forces oil through a pipe 108 having branches 110 and 112 which deliver the oil to 105 the bearings in the pump-head from which the oil drains back to the reservoir 100 through a pipe 114 indicated in Fig. 11. 110

Fig. 13 shows a floating stuffing-box which may be used for the rods 46 or the rod 16. 115 A free stuffing-box 119 provided with a recessed cover 120 has an enlarged flanged portion 121 adapted to move laterally between the casing 38 and a recessed retaining member 122 which is bolted to the casing 115 38. This capacity for slight lateral movement allows the rod to assume its natural position at all times whether free or under load and to accommodate itself to the errors of alinement common to this class of machines. 120

I claim:

1. A pump comprising a base and a casing mounted thereon, planetary gear mechanism in said casing mounted in pairs and spaced apart, a crank pin connected to said planetary gear mechanism and extending across said space and reciprocable by the gear mechanism in a straight line, a multiplicity of pump rods passing through said base and 125 130

- within the space in said casing, and means connected directly with said crank pin for operating all of said pump rods.
2. A pump comprising a base and a closed casing mounted thereon, planetary gear mechanism in said casing mounted in pairs and spaced apart, a crank pin connected to said planetary gear mechanism and extending across said space and reciprocable by the gear mechanism in a straight line, a multiplicity of pump rods, a corresponding number of stuffing boxes in said base through which said pump rods extend to within the casing, and means connected directly with said crank pin for operating all of said pump rods.
3. A pump comprising a casing forming a chamber, planetary gear mechanism mounted in said chamber, a pump rod, means connecting said pump rod with the gear mechanism for reciprocating the end of the rod back and forth across said chamber, a second pump rod having a pair of arms extending in parallel spaced relation relative to the first pump rod and mounted for movement back and forth across said chamber, and means for operating said second pump rod from the first pump rod, substantially as described.
4. A pump comprising planetary gear mechanisms mounted in pairs and spaced apart, a crank pin connected to said planetary gear mechanism and extending across said space and reciprocable thereby in a straight line, a pump rod connected to said crank, a second pump rod having a pair of arms connected therewith movable in the plane of the first named pump rod on either side thereof and within the space between the sets of planetary gears, and means operated by the crank pin for actuating the pair of arms to reciprocate the second pump rod in opposite direction to that of the first pump rod, substantially as described.
5. A pump comprising a casing embodying an upper and a lower chamber, planetary gear mechanism mounted in the lower of said chambers, a pump rod, means connecting said pump rod with the gear mechanism for reciprocating the end of the rod back and forth across said lower chamber, a double rack connected at its lower end with the upper end of the pump rod and adapted to reciprocate back and forth across said lower chamber, two other pump rods mounted for simultaneous movement back and forth across said lower chamber and having racks on the ends thereof, all of said racks being movable in both chambers, and means for driving the second named racks from the double rack.
6. A pump comprising a casing embodying an upper and a lower chamber, a rotary member in the lower chamber, a pump rod having connection with said rotary member and reciprocated thereby back and forth across said lower chamber, a rack connected with the pump rod and reciprocated thereby back and forth across said lower chamber and into the upper chamber, a second pump rod, and means connected with said second pump rod, and movable back and forth across said lower chamber and into the upper chamber, said connecting means being operated by the rack.
7. A pump comprising a pump-head, a support for said pump-head, a spider adapted to be held in position by said support, pump rods adapted to be operatively attached to said pump-head, a drop pipe supported from said spider, and means for leveling said spider in order to bring said pump rods and said drop pipe into axial alinement relatively to each other.
- In testimony whereof I hereunto affix my signature.
- EDWARD E. JOHNSON.
